UNITED STATES PATENT OFFICE.

ANNA T. SCHNEIDEWENDT, OF CHICAGO, ILLINOIS.

KINDERGARTEN LOOM.

Application filed September 30, 1922. Serial No. 591,528.

To all whom it may concern:

Be it known that I, ANNA T. SCHNEIDEWENDT, a citizen of the United States, residing at Chicago, in the county of Cook and State of Illinois, have invented certain new and useful Improvements in Kindergarten Looms, of which the following is a specification, reference being had to the accompanying drawings.

10 This invention relates to looms, and has for its object to provide a loom operated by hand for weaving articles which require the woof of the weave to extend beyond the warp.

15 It is also an object of the invention to provide a loom of this character wherein each pick of the woof is accomplished by means of a needle.

20 It is a further object of the invention to provide a loom of this character including means for supporting the warp, and means for supporting the woof a predetermined distance from the warp.

25 With these and other objects in view, the invention consists in the improved construction and arrangement of parts to be herein-after more particularly described, fully claimed and illustrated in the accompanying drawings, in which:—

30 Figure 1 is a perspective view of a loom constructed in accordance with an embodiment of the invention;

Figure 2 is a top plan view showing the loom in use; and

35 Figure 3 is a perspective view of the needle.

Referring to the drawings, 5 designates a base member comprising elongated strips 6 and 7 which are spaced from each other and 40 connected by relatively small end strips 8 and 9, the strips 8 and 9 being disposed upon the strips 6 and 7. By this means a substantially rectangular frame is provided. It is of course obvious that this frame may be 45 made in various lengths and widths.

In order to support the warp on the loom frame, warp holding members 10 and 11 are provided, each of said members consisting of a plate having its upper edge recessed at 50 spaced intervals to provide a plurality of teeth 12, said teeth terminating inwardly of the corners of the plate. Each tooth is intended to receive a portion of the warp. The plates 10 and 11 are disposed at the central portion of the frame, the plate 10 being

secured to the strip 6 exteriorly thereof, while the plate 11 is secured to the strip 7 exteriorly thereof. The plates 10 and 11 are, however, disposed so that the teeth 12 thereof are in alignment, to assure an even 60 weaving of the material.

The end portions of each of the plates 10 and 11, adjacent the teeth 12, are provided with openings 13, the openings of one plate registering with the openings of the opposite plate. These openings are intended to receive pins 14 and 14^a, each pin including a head 15, while the opposite end 16 projects beyond the plate through which it passes and provides means to which the ends of 70 the warp may be secured.

Projecting from each end portion of the frame are woof holding arms 17, said arms being secured to the ends of the strips 6 and 7 and are braced by the end strips 8 and 9, 75 as the strips 8 and 9 are disposed inwardly of the arms and above the end portions of the strips 6 and 7. The length of the arms 17 corresponds to the height of the plates 10 and 11. The arms 17 however, are disposed in spaced relation to the plates 10 and 11. Each arm is provided with an opening 18 adjacent its upper end, adapted to register with an opening in the corresponding end of the opposite arm. These registering 80 openings are intended to receive pins 19 and 19^a, each pin including a head 20 and having its opposite end 21 arranged to extend beyond the arm through which it passes similar to the pins 14 and 14^a, to provide securing means for the ends of the woof.

85 In connection with the loom, a needle is used. This needle consists of a length of material 22, preferably rectangular in cross section. The end 23 is tapered to provide a needle point, while the opposite end is provided with an elongated or elliptical eye 24 adapted to receive the woof material.

90 In operation, the warp may be of any desired material, either in cord form or strips. The end of the warp is secured to the projecting end portion of the pin 14^a. It is then passed through the recesses between the teeth and around the first tooth of the plate 11, through the recess adjacent said tooth, and around the opposite tooth of the plate 10, and so on until the warp has been passed between all the teeth of warp holding means. The end of the warp is then secured to the 105 projecting end portion of the pin 14, the 110

warp being of course tightly held or stretched. It is obvious that the pins 14 and 14^a are disposed below the upper ends of the teeth so as not to interfere with the warp in the weaving operation. The woof material has one end thereof secured to the projecting end of the pin 19^a, the woof being of course threaded in the eye of the needle 22. The woof is extended longitudinally of the frame 10 under the pin 14^a, then over and under the warp in the usual manner, and under the pin 14. The woof is then continued to the pin 19 over and under said pin and then back again over the pin 14 and woven through the 15 warp and over the pin 14^a. This operation is continued until the woof has been extended the entire width of the loom. No tightening of the woof is necessary. If additional woof material is necessary the end 20 of said material may be twisted around either one of the pins 19 or 19^a, according to the position of the exhausted end of the previous woof, and then used in the manner 25 above described. In this way the ends of the woof are always disposed at either one of the pins 19 or 19^a.

When the weaving operation has been completed the pins 14 and 14^a are removed from the warp supporting members after 30 the ends of the warp have been removed from the pins. The warp may then be lifted from the teeth of the plates 10 and 11 so as to disengage the woven material from the warp supporting members. The loop 35 ends of the woof are then released by removing the pins 19 and 19^a from the arms 17. The woof material is then laid flat on the support and the projecting ends of the woof cut off even with the remaining portions of the 40 woof. The projecting ends of the warp are then extended into the weaving by means of a sack needle until said ends disappear, thus

eliminating the necessity of knotting the ends.

This loom is particularly adapted for 45 weaving mops, and is exceedingly valuable as an educational device for use in schools teaching the industrial arts. It is small and compact and can be easily operated by a child without any knowledge of weaving. 50 In addition to this it is composed of only a small number of simple parts all of which are stationary, so that there is no danger of the loom getting out of order when handled by a person not familiar with its construction. It is of course obvious that I do not desire to be limited to the construction shown, as it is possible to increase the length of the warp holding members so as to provide a loom for weaving mats having fringe 60 on the ends thereof, and like articles. All of these features are possessed by a device that can be inexpensively manufactured in large quantities from a small amount of material. 65

What is claimed is:—

A loom comprising an elongated base, a pair of arms carried by each end portion of the base, the arms of each pair being disposed in spaced relation to each other, woof holding pins movably supported by the arms 70 in spaced relation to the base and in parallel relation to each other, warp holding plates carried by the central portion of the frame in alignment with each other, the upper edge of each plate being provided with 75 a plurality of teeth arranged to engage and hold the warp of the material, and pins extending between and connecting the plates to each other, said pins providing means for holding the ends of the warp. 80

In testimony whereof I hereunto affix my signature.

ANNA T. SCHNEIDEWENDT.
